UNITED STATES PATENT OFFICE.

HENRY K. BURKET, OF OMAHA, NEBRASKA.

BURIAL-ROBE.

SPECIFICATION forming part of Letters Patent No. 702,773, dated June 17, 1902.

Application filed March 24, 1902. Serial No. 99,757. (No model.)

To all whom it may concern:

Be it known that I, HENRY K. BURKET, a citizen of the United States, residing at Omaha, in the county of Douglas and State 5 of Nebraska, have invented certain new and useful Improvements in Burial-Robes; and I do hereby declare the following to be a full, clear, and exact description of the invention, such as will enable others skilled in the art 10 to which it appertains to make and use the same.

My invention relates to burial-robés; and the object of the invention is the production of a robe which can be very conveniently and 15 quickly placed on the body and which when in position will have the appearance of being a completely-finished garment of ordinary construction. Burial-robés manufactured solely for such purpose are coming extensively into use, and the custom is being extensively adopted of using such robes in lieu of the practice heretofore adopted of dressing the remains in the clothing which they wore in life. As is well known, considerable 20 difficulty is experienced in properly placing the garments upon the corpse after it has been prepared for burial, and it is to facilitate this operation that my invention is designed.

In the accompanying drawings, Figure 1 is 25 a perspective view of a garment constructed in accordance with my invention. Fig. 2 is a perspective view of a portion of the same, showing that side of the garment which carries the collar and the securing-strings, the view being taken from the inside of the garment when the latter is in open condition. Fig. 3 is a transverse section through the garment, showing the manner of securing the same in front and concealing the fastening 30 means; and Fig. 4 shows the invention applied to a garment designed to be worn by men and boys, the same being shown in the form of a union garment—that is, a coat and vest combined.

The garment comprises a suitable body portion which is open down the back, as at 1, from the upper edge thereof, for about five or six inches. The portion of the garment to the left of the opening, which I will mark 2, 45 and which is shown in detail in Fig. 2 looking at the garment when laid out flat in an open condition, carries a collar 3 and securing-

strings 4. One end 5 of the collar extends a short distance beyond the edge of the body portion, so that when the two ends of the collar 55 are brought into position the projecting portion 5 will slightly overlap the other end of the collar 6, or at least allow for the desired adjustment at this point to make a neat fit about the neck, the collar being held in position by 60 means of the securing-strings 4. This portion 2 of the garment which carries the collar is provided with a plurality of fastening means, preferably hooks or eyes, as 7, arranged in a vertical row on the inside of the garment, as 65 clearly shown in Fig. 2, and the other portion of the garment to the right of the opening in the back, which for convenience I will mark 8, is provided on its vertical edge with a plurality of fastening means, preferably hooks 70 or eyes, as 9, which are designed to engage the fastening means 7 by bringing the portion 2 of the garment over and upon the portion of the garment marked 8. The vertical edge of the portion 2 of the garment is also 75 provided with a plurality of fastening means, such as hooks or eyes, as 10, which when said portion 2 is brought over upon the portion 8 of the garment engage fastening means, as 80 hooks or eyes 11, provided on the said portion 8. To conceal this latter fastening means from view, the portion 8 of the body portion is provided with a vertical fold 12, which extends practically the entire length of the body portion and which extends over the fastening 85 means 11 and beneath which the vertical edge of the portion 2 of the garment, carrying the fastening means 10, is extended, so that said fastening means will be entirely concealed from view. To give an ornamental appearance to the front of the garment, the portion 2, carrying the collar 3, is provided with any suitable ornamentation, as chiffon, for instance. The garment will be provided with sleeves of any suitable description. The robe 90 can be made any style front and can fasten with either buttons or hooks and eyes, preferably the latter. The skirts are usually sold with the waist and can be made a part of the waist or separate from the same.

By the use of my invention the necessity of slitting the garment back and front, which is found to be very objectionable to undertakers and funeral directors, is obviated.

In Fig. 4 I have shown a modified construction of my invention, in which it is applied to a combined coat and vest, forming a union garment, the coat being open at the front and 5 provided with fastening means, as 13, and with an opening 14 in the back, and securing-strings 15 for bringing the ends together and securing them in position.

In dressing remains in waist or coat the 10 operation would be about as follows: Open the front of the robe and place the garment over the remains with the bottom of the back part of the robe at the chin and the collar toward the feet. In this position place the 15 arms in the sleeves, drawing the sleeves up around the wrist. Then have an assistant raise the hands up to the top of the head. Then gather the back of the garment in your right hand and with your left hand raise the 20 head. Then slip the right hand over the head with the back of the garment inclosed in your hand. Then pull the sleeve down to the shoulders and the back of the garment down, and the garment is in position. The 25 opening at the neck renders it easy to slip the garment over the head and also enables one to adjust the collar to fit any size neck.

Having thus fully described my invention, what I claim as new, and desire to secure by 30 Letters Patent, is—

1. A burial-robe, open at front and provided with an opening at the back from its upper edge downward for a suitable distance, the portion of the garment to one side of the rear 35 opening carrying a complete collar, and means for securing the collar in position, substantially as described.

2. A burial-robe, open at front and provided with an opening at the back from its upper 40 edge downward for a suitable distance, the portion of the garment to one side of the rear opening provided with an integral complete collar, means for securing the collar in position, and fastening means for securing the 45 garment in position in front, substantially as described.

3. A burial-robe, open at front and provided with an opening at the back extending from the upper edge thereof downwardly for a short 50 distance, the portion of the garment to one side of the rear opening provided with an integral complete collar, one end of the collar projecting beyond the edge of the garment, so that it can be adjusted to fit any size neck,

and fastening-strings for drawing and holding the ends of the collar to position, and fastening means for securing the garment in front, substantially as described. 55

4. A burial-robe, open at front and provided with an opening at the back extending from 60 the upper edge thereof downwardly for a short distance, the portion of the garment to one side of the rear opening provided on its inner side with a plurality of vertically-arranged fastening means which engage fastening 65 means on the vertical edge of the other portion of the robe on the other side of the rear opening, and another set of vertically-arranged fastening means on the edge of the first-mentioned portion of the garment, which 70 engage fastening means arranged on the second-mentioned portion of the garment, said latter fastening means being located back of the edge fastening means, and a fold carried by the second-mentioned portion which laps 75 over and conceals the last-mentioned fastening means, and means for securing the garment at the neck, substantially as described. 80

5. A burial-robe, open at front and provided with an opening at the back extending from 85 the upper edge thereof downwardly for a short distance, a portion of the garment to one side of the rear opening provided with an integral complete collar, fastening-strings for drawing and holding the ends of the collar to position, 90 said portion of the garment provided on its inner side with a plurality of vertically-arranged fastening means, which engage fastening means on the vertical edge of the other portion of the garment on the other side of the rear opening, and another set of vertically-arranged fastening means on the edge of the first-mentioned portion of the garment, which 95 engage fastening means arranged on the second-mentioned portion of the garment, said latter fastening means, and a fold carried by the second-mentioned portion which laps over and conceals the last-mentioned fastening means, and means for securing the garment at the neck, substantially as de- 100 scribed.

In testimony whereof I hereunto affix my signature in presence of two witnesses.

HENRY K. BURKET.
